US00D869560S

(12) **United States Design Patent** (10) Patent No.: **US D869,560 S**
Schultheis et al. (45) Date of Patent: **** Dec. 10, 2019**

(54) **PLAYING SURFACE FOR SPINNING TOP
TOY**

(71) Applicant: **TOMY COMPANY, LTD.**, Tokyo (JP)

(72) Inventors: **Douglas Arthur Schultheis**,
Cumberland, RI (US); **Ramon Antonio
Campos**, Pawtucket, RI (US);
Michelino Paolino, Jr., Rumford, RI
(US); **Luke Lohan**, Abington, MA (US)

(73) Assignee: **TOMY COMPANY, LTD.**, Tokyo (JP)

(**) Term: **15 Years**

(21) Appl. No.: **29/632,136**

(22) Filed: **Jan. 5, 2018**

(51) LOC (12) Cl. **21-01**

(52) U.S. Cl.

CLAIM

The ornamental design for a playing surface for spinning top toy, as shown.

DESCRIPTION

FIG. 1 is a front view of the playing surface for spinning top toy showing our design;

FIG. 2 is a left side view thereof;

FIG. 3 is a rear view thereof;

FIG. 4 is a right side view thereof;

FIG. 5 is a top view thereof;

FIG. 6 is a bottom view thereof;

FIG. 7 is a perspective view thereof;

FIG. 8 is a front disassembled perspective view thereof; and,

FIG. 9 is a rear disassembled perspective view thereof.
